UNITED STATES PATENT OFFICE.

EVARTS G. LOOMIS, OF NEWARK, NEW JERSEY, ASSIGNOR TO ST. MUNGO MANUFACTURING COMPANY OF AMERICA, OF NEWARK, NEW JERSEY, A CORPORATION OF NEW JERSEY.

BALL-WINDING MACHINE.

1,242,885.

Specification of Letters Patent.

Patented Oct. 9, 1917.

Application filed October 14, 1915. Serial No. 55,757.

To all whom it may concern:

Be it known that I, EVARTS G. LOOMIS, a citizen of the United States, and resident of Newark, county of Essex, and State of New Jersey, have invented certain new and useful Improvements in Ball-Winding Machines, of which the following is a specification.

The invention relates to machines for winding balls such as are known as playing balls. The machine is particularly designed to carry out in a practical manner the winding of a rubber thread or tape about a central core so as to form a larger spherical core or ball for use in the manufacture of golf balls.

As showing a specific embodiment of the invention reference is made to the drawings forming a part of this specification, in which drawings,

Figure 1 is a vertical cross sectional view of the machine taken as on the line 1—1 of Fig. 4. In Fig. 1 the parts are shown in the position which they occupy when the core has been wound and removed from engagement with the driving or supporting rollers of the machine.

Fig. 2 shows certain parts in the position which they occupy while the core is being wound.

Fig. 3 is a vertical and longitudinal sectional view taken as on the planes indicated by the broken line 3—3 of Fig. 1.

Fig. 4 is a partial plan view of the winding machine. In this view some of the covers have been removed so as to show the operating parts more clearly.

Fig. 5 shows in longitudinal section the details of the roller construction; and

Fig. 6 is a front elevation of the ejector lever showing a portion of the resetting and operating link which is connected to it.

The machine is provided with any suitable frame as "1" upon which the several parts of the machine are mounted. The balls or cores which are to be wound are indicated by "A—A". Fig. 2 shows the position of a ball or core while being wound and Fig. 1 shows the ball or core in the position which it occupies at the end of the winding operation.

The machine comprises a pair of parallel rollers "2, 2" which may be referred to as supporting rollers or as driving rollers, ar-

ranged a suitable distance apart so as to serve as a support for the core or ball being wound, and also to drive or rotate the core or ball for the purpose of winding the thread upon it.

A mechanism "3" is provided to rotate these supporting rollers and also to impart a longitudinal movement to the rollers relative to each other, and as will hereinafter appear the rollers reciprocate longitudinally as they rotate. The relative longitudinal movement between the rollers is provided to shift the balls laterally so as to constantly change the course of the thread or tape whereby the product which is formed in the machine will have a spherical form.

The machine is also provided with roller mechanism "4" which forces the core or ball being wound against the supporting rollers until the core or ball has reached the desired size.

The material which is to be wound upon the ball is supported as at "5" and passes over the tensioning and guiding means "6" prior to being wound. The machine is also provided with an ejector mechanism "7", the function of which is to lift the ball or core from engagement with the driving rollers when it has reached the desired size and this is accomplished in the machine shown by mechanism which is caused to be operated when the ball or core has moved the holding roller "4" and its carrying frame the desired distance.

As previously indicated, the rollers "2, 2" are spaced a sufficient distance apart to provide a suitable receiving space for a ball or core such as a core of solid rubber or a core having liquid contained in a casing. These rollers "2, 2" must be close enough together however to serve as a suitable support for the core to be wound and also such a distance apart that they will be able to rotate or drive the core to be wound without throwing the core out of the machine.

The core or ball while being wound is engaged as is shown in Fig. 2 by the holding roller "4" which is preferably a split roller. This split roller "4" is carried in the forward free end of an arm "8" that is pivotally mounted on the frame at "9".

The frame has a rigid upstanding arm "10" so as to provide an abutment for the nut "11" in which the screw-member "12"

is located. A link "13" passes through the screw "12" and is pivotally connected to the arm "8" at "14". As the upper end of the link "13" is provided with a threaded nut "15" it can be utilized as a stop to determine the lowest distance which the arm "8" can occupy. This arm is normally pressed toward its lowest position by the coil compression-spring "16" that surrounds the link. One end of this spring "16" 10 presses against the arm "8" while the other end of the compression-spring presses against the lower face of the screw "12". The arm "8" is provided with a handle "8a" whereby the operator of the machine can lift the arm "8" and the pressing roller "4" 15 when he desires to insert a core in place in the machine or when he desires to remove a core from the machine.

20 The ejector "7", heretofore referred to, comprises a lever or arm "17" that is pivotally mounted on the frame at "18" and to this lever or arm "17" there is pivotally connected a link "19". The lower end 25 of the link "19" is connected to the operating lever "20" whereby by pushing downwardly on the free end of the lever "20" the ejecting mechanism can be reset. An adjustable collar "21" is carried on this 30 link "19" and against this collar there presses the upper end of a compression-spring "22". The lower end of this compression-spring presses against the table upon which the machine is carried and the function 35 of this spring is to press the ejecting lever toward ejecting position. The ejecting lever "17" is provided with the up-standing portion "23" which when engaged at "24" by the latch or catch "25" serves to 40 hold the ejector in inoperative position. The latch or catch "25" has a handle "26" whereby the latch may be released by hand and it is also provided with the depending portion "27". The movable frame or arm 45 "8" has an integral upstanding arm "28" on which there is mounted an adjusting screw "29." This screw "29" is arranged so that it can engage the depending portion "27" that is on the catch "25" so that as a ball 50 or core "A" forces the pressing roller "4" upwardly with its increase in size the upper end of the arm "28" will be moved rearwardly and the latch "25" will be released from engagement with the member "24" 55 due to the screw "29" engaging and moving the depending portion "27" on the latch.

The main shaft "30" of the machine is carried in any suitable bearings as "31" and upon one end of this shaft there is mounted the driving gear "32" and at the other end through the tight and loose pulleys "34" and "35", respectively. In mesh with the

driving gear "32" are the two gears "36, 36" 65 the latter of which are secured to or integral with the spindles upon which the supporting and driving rollers "2, 2" are secured. The bevel gear "33" meshes with the bevel gear "37," which, through the medium of the pin "38," drives the upper and lower cams "39" and "40". The bevel gear "37" rotates around a fixed bearing, to wit, about the shaft "41."

The cams "39" and "40" are clearly shown 75 in Figs. 3 and 4 and a portion of one of these cams is indicated at the right hand of Fig. 5. The gears "36" are the gears through which the rotary movement is imparted to the rollers from the driving gears 80 "32". The relative longitudinal movement between the rollers is imparted to the rollers by means of the cams just referred to. These cams each reciprocate, in a longitudinal direction, the supporting roller which it 85 controls. The mechanism whereby this is enabled to be accomplished will be presently described.

A detail of the supporting roller mechanism is shown in Fig. 5. In actual practice 90 the roller "2" is made of an aluminum casting which is secured by means of the pin "42" to a spindle "43", preferably of steel, and it is upon this spindle "43" that the gear "36" is located. For the sake of lightness and compactness of structure each of these spindles is made hollow for a comparatively large portion of its length. The righthand end of this spindle is provided with a thrust bearing made of hardened 95 steel at "44". The spherical end of this bearing member "44" engages a hardened plate "45" that is located in the cavity of the socket member "46". The socket member 100 "46" has an anti-friction roller "47" which 105 presses against the cam partially shown in said Fig. 5.

Each of the rollers "2" is normally forced toward the right so that the roller "47" will engage its proper cam by means of the compression spring "48", part of which spring extends into a hollowed portion "48a" in the spindle. One end of this spring rests at "X" against a part on the frame and the other end of the spring engages at "Y" with the thrust bearing member "49". The thrust bearing of which the member "49" is a part 110 also comprises the hardened steel plate "50" and the spherical ended member "51". Both the parts "50" and "51" are preferably made 115 of a hardened steel and are arranged so that a spherical end on the member "51" engages a flat surface on the member "50". The spring "48" surrounds a hollow rod or tube "52" through which oil may be inserted to 120 the bearing. This rod also serves to maintain the spring in proper form. It will thus be observed from an inspection of this figure 125

when taken in conjunction with Fig. 3 that each of the rollers "2" can be forced by the cams toward the left against the compression of the respective springs and that these 5 springs serve in turn to force the rollers to the right as they are permitted to do so by the movement of the cams. An inspection of Fig. 4 will furthermore make it clear that for each revolution of each cam there 10 are several reciprocatory movements for each of the supporting rollers and it will also be observed that the cams are of such a shape and arranged so that there is a relative longitudinal movement between the 15 rollers. These cams have been designed so that due to the longitudinal movement of the rollers they will cause the balls or cores to turn laterally while they are rotating the 20 balls or cores in a proper direction to wind a thread or tape upon them.

The ejector mechanism is made so that it will remove a ball or core from the supporting rollers when the ball or core is of the proper size and it will therefore be manifest 25 that a number of balls or cores can be wound simultaneously upon the same machine provided a number of holding and ejecting mechanisms are arranged in co-operative relation to the supporting rollers. For each 30 holding and ejecting mechanism there is also provided a guiding and tensioning means and this is indicated by the reference character "6" in Fig. 2.

The path of the thread or tape from its 5 source of supply "5" to the core or ball "A," where it is wound, is through the guide opening "53," over the flat idler wheel "54," the flat face wheel "55" and the grooved wheel "56" to the core "A." The flat face wheel "55" and the grooved wheel "56" have between them the chain of gearing comprising the spur wheels indicated by "57," "58" and "59." The ratio of this gearing is such that a determined tension or elongation will be imparted to the thread or tape as it passes over and in engagement with the guiding rollers or wheels "55" and "56." This portion of this apparatus may be referred to as a tensioning or elongating means and also as a part of a guiding means. The roller "54" is mounted on an arm "65" which can be retracted against the pressure of the spring "60." One end of this spring "60" presses against the arm at "61" while the other end of the spring is secured at "62" by means of the split collar "63" that can be clamped in the desired position by the screw "64."

In the operation of the machine, a core is placed on the supporting rollers and the pressing roller "4" is brought to the position shown in Fig. 2. As the operation proceeds, the core or ball is caused to turn in the direction of the arrows shown in Fig. 2, and the

core is also given a partial lateral rotation 65 by the relative longitudinal movement that is imparted to the rollers "2, 2" by the cams. The rubber thread or tape is drawn from the source of supply "5" over the guiding means which comprises said tensioning 70 means and it is stretched the desired distance by the rollers "55" and "56" which have different speeds of rotation. In other words, the surface speed of the roller "55" 75 (and also the surface speed of the roller "54") is slower than the surface speed of the roller or wheel "56." It will be observed that the flat idler wheel "54," flat face wheel "55"—which latter may be considered the advance geared wheel of the geared set—and 80 the grooved wheel "56"—which may be considered the rear geared wheel of the geared set—are all free to rotate. In other words, the wheels "54," "55" and "56" are propelled by the rubber strip itself—be it in the form 85 of a thread or tape—as the strip is drawn over these wheels during the winding operation. As above indicated, the ratio of the gearing between the advance wheel and the rear wheel is such as to cause a substantially 90 lower rate of speed of the periphery of the advance wheel than the grooved or rear wheel and there will necessarily result a substantial elongation—in actual practice approximately 800%. The construction comprising 95 the geared wheels may be referred to, as previously indicated, as a tensioning device, and is particularly applicable to machines for winding rubber upon the cores of playing-balls, still it is to be noted that 100 this tensioning device may be employed in other machines where it is desired to elongate or stretch strands. When the ball or core has reached the desired size it raises the split roller "4" a sufficient distance from 105 the supporting rollers for the split roller in turn to lift the frame to the position where the catch "25" is released, thus allowing the ejector "7" to remove the ball or core from the rollers "2, 2." In order that a ball "A" 110 will be retained between the ejector and the holding rollers "4," a depending member "60" having a roller "60a" which is arranged on the arm "8" so that the roller "60a" will engage the ball or core on the rear side. The 115 split holding roller "4" engages the ball slightly ahead of the center and so does the ejector and thus a three-point engagement with the ball or core is provided which will properly hold the core or ball until it is removed from the machine by the operator. 120

While the machine is particularly adapted for the winding of rubber on the core of golf balls, still it will be manifest that the winding machine is adaptable for the winding of 125 other materials on the cores of other playing balls.

The improvements herein set forth are not

1 limited to the precise construction and arrangement shown and described, as they may be embodied in various forms and modifications without departing from the spirit and 5 scope of the invention.

I claim:

1. A ball-winding machine comprising in combination parallel rollers which move longitudinally relative to each other, means 10 for rotating said rollers, means for pressing a ball or core against said rollers as the latter is being supported by and driven by said parallel rollers, and means coöperating with said pressing means for lifting the ball 15 or core from said parallel rollers when the ball or core has reached the desired size.

2. The combination in a ball-winding machine of parallel supporting rollers, means for rotating said rollers and for moving 20 them longitudinally relative to each other, pressing mechanism comprising a roller which is located above said supporting rollers, and ejecting means coöperating with said pressing mechanism, which ejecting 25 means is constructed so that when the pressing roller reaches a determined position relative to the supporting rollers the ejecting means will be allowed to operate in a manner to remove a ball or core, that is engaged 30 by the presser roller, from the position where the ball or core will be driven by said supporting rollers.

3. A ball-winding machine of the class described comprising in combination supporting rollers which have relative longitudinal movement, a holding or pressing roller located above the supporting rollers, an ejector located between the supporting rollers, and means coöperating with the 35 40 ejector and the holding roller whereby the ejector will be allowed to operate when the holding roller has been moved away from the supporting rollers a determined distance.

4. A machine of the class described comprising in combination parallel supporting and driving rollers, means for rotating said rollers, means for causing a relative longitudinal movement between said rollers as 45 50 they rotate, a pivotally mounted ejector having the free end of one of its arms located between said parallel rollers, a pivotally mounted arm having at its forward end roller means for holding a core, while being wound, in engagement with said parallel rollers and means coöperating with said pivotally mounted members whereby, when the core reaches a certain size, the ejector will be brought into operation to remove the core 55 60 from said supporting rollers.

5. A ball-winding machine of the class described comprising in combination supporting rollers, a holding roller located above said supporting rollers for normally pressing a core or ball against said supporting rollers,

which holding roller is located so as to engage the core, being wound, slightly forward of the vertical line passing through said core, a member for engaging the core, when wound, on the side which is rear of 70 said vertical line, and an ejector for engaging the underside of the core in a manner to remove the core from the supporting rollers and to hold the core in removed position while the latter is in engagement with the holding roller and the member which engages the core at the rear.

6. A ball-winding machine having parallel supporting rollers, a movable member having thereupon roller means for holding a core, while being wound, in engagement with the supporting rollers, which roller-holding means is located above the supporting rollers, an ejector that extends into the space between the supporting rollers, and means coöperating with the movable member having thereupon the holding roller and with the ejector whereby when the holding roller means has been raised a certain distance from the supporting rollers the ejector will be caused to operate, said movable member also having thereupon a ball retaining member which serves to help hold the core in raised position when the latter is engaged by the holding roller means 95 and the ejector.

7. A ball-winding machine comprising in combination parallel supporting rollers, a movable member carrying thereupon a holding roller, which movable member is constructed and arranged so that the holding roller can be forced toward the supporting rollers by a spring means which constitutes an element in the machine, an ejector arranged so as to lift the core from engagement with the supporting rollers, and mechanism comprising a releasing catch or latch which permits the ejector to operate when the holding roller reaches a certain position relative to the supporting rollers. 100

8. A machine of the class described comprising in combination a frame, supporting rollers carried thereby, means for rotating said rollers, means for imparting reciprocating movement in a longitudinal direction 105 to said rollers and for imparting a relative longitudinal movement between said rollers, a pivotally mounted arm having at the forward end thereof a split roller for holding the core being wound in engagement with the supporting rollers, said split roller being located above the supporting rollers, an adjustable spring means normally forcing the split roller toward the supporting rollers, an upwardly extending arm integral with the 115 forwardly extending arm above referred to, a pivoted catch, an adjusting screw at the upper end of the upwardly extending arm, which screw serves to move the catch when the split roller has been raised to a certain 120 125 130

- point, a spring-actuated ejector having a portion thereof arranged so that it extends between the supporting rollers in a manner so that it can lift the core or ball from the 5 supporting rollers when the ejector is allowed to operate, said ejector having a member which coöperates with the catch so as to hold the ejector from operating until released.
- 10 9. A ball-winding machine of the class described having in combination parallel driving rollers, means for imparting relative longitudinal movement between the rollers as they are rotated, and a split roller located 15 above the driving rollers for forcing the core or ball to be wound into engagement with the driving rollers, said driving rollers being provided on their driving faces with a casting made of aluminum.
- 20 10. A machine for winding a rubber thread or tape upon a core, which machine comprises in combination a pair of supporting and driving rollers, each having upon its driving face a casting of aluminum, 25 means for rotating said rollers, means for imparting relative longitudinal movement between said rollers, a holding roller located above said driving rollers, and means for guiding a rubber thread or tape to the core 30 as the latter is being wound in the machine.
11. A machine of the class described comprising in combination a frame, a main driving shaft carried by said frame, a main gear on said shaft, a pair of supporting 35 rollers mounted in bearings on the frame so as to permit of a relative longitudinal movement between them, each of said rollers having a gear which coöperates with the main gear, which said roller gears are constructed so that relative longitudinal movement between them can take place as the 40 main gear drives the roller-gears, the main shaft also having a bevel gear which in turn coöperates with a second bevel gear that 45 drives two cams, one of which cams controls the longitudinal movement of one of the
- supporting rollers, while the other of said cams controls the longitudinal movement of the other of said rollers.
12. A machine of the class described comprising in combination a pair of parallel supporting rollers each of which are continuously spring-pressed toward a cam, a holding roller located above the supporting rollers, means for rotating the supporting 50 rollers and for also simultaneously reciprocating longitudinally the supporting rollers, which means comprise a pair of cams arranged upon a common shaft, one of which cams controls the longitudinal movement of one of the supporting rollers and forces it against its spring, and the other of which cams controls the longitudinal movement of the other supporting roller and forces it against its spring, the cams being constructed and arranged so that at times there is a 55 relative longitudinal movement between the rollers.
13. In a ball-winding machine the combination of a frame, bearings carried by the 60 frame, a driving roller having a spindle passing through said bearings, a cam carried on a shaft which is mounted in bearings on said frame, a socket member which surrounds one end of said spindle and which 65 socket-member has a roller that engages said cam, a stem carried by said frame and entering a socket in said spindle, coöperating thrust bearing members located in said socket, and a spring located between said 70 frames and one of said thrust bearing members and extending into said socket there being a driving gear secured to said spindle and also a thrust bearing between the spindle and the socket-member which carries the 75 roller that engages the cam.
